ATTORNEY

UNITED STATES PATENT OFFICE

EDWARD WYATT DRENNAN, OF BAKERSFIELD, CALIFORNIA

WIRE CUTTER

Application filed January 25, 1929. Serial No. 335,130.

This invention relates to a wire cutter which is mainly used for cutting the wire which ties portions of concrete forms together, the general object of the invention being to provide 5 a shank having a spear-shaped head with a beveled flange extending from its front face, the cutting edge of the flange merging into the point of the head so that the device can be readily passed between a wire and a post 10 or other part around which the wire passes and by exerting slight force on the device, the wire will be cut.

Another object of the invention is to provide means whereby handles of different 15 lengths can be readily attached to the shank so that the device can be used for cutting wires at a distance from the operator and also for cutting wires on those portions of the forms which are in excavations.

20 This invention also consists in certain other features of construction and in the combination and arrangement of the several parts, to be hereinafter fully described, illustrated in the accompanying drawing and specifically 25 pointed out in the appended claim.

In describing the invention in detail, reference will be had to the accompanying drawing wherein like characters denote like or 30 corresponding parts throughout the several views, and in which:—

Figure 1 is a fragmentary view of a cement form, showing the invention in use for cutting the tie wires thereof.

Figure 2 is a side view of the device.

35 Figure 3 is a front view thereof.

Figure 4 is an end view.

In these views, the numeral 1 indicates the shank of the tool and 2 indicates a spear-like head which is formed with the shank. A 40 flange 3 is formed on the front face of the head, the outer edge of the flange tapering from its rear to the front, where the flange merges into the pointed end of the head, the 45 point formed by the head and flange being of triangular shape in cross section. The outer edge of the flange is beveled to form a cutting edge so that when the tool is forced between a tie wire and a post or other part 50 of the form carrying the wire and a slight

pressure is exerted on the tool, the wire will be cut by the beveled edge of the flange.

A coupling 4 is threaded to the free end of the shank so that handles, such as shown at 5, 55 can be connected with the shank, any desired length of handle being usable with the device. As shown, the handle is simply a length of tubing having one end threaded to engage the coupling.

By providing the device with a long handle, 60 an operator can stand at a certain point and cut all the wires along a post, as shown in Figure 1, without changing his position, and this device enables the wires to be cut from 65 those portions of the form arranged in an excavation so that it is not necessary for the cutter to go into the excavation.

It is thought from the foregoing description 70 that the advantages and novel features of the invention will be readily apparent.

It is to be understood that changes may 75 be made in the construction and in the combination and arrangement of the several parts, provided that such changes fall within the scope of the appended claim.

What I claim is:—

Means for cutting tie wires of a concrete form comprising a shank, a spear-shaped head formed with the shank, the head ending 80 in a point with the edges of the pointed part beveled to form cutting edges, an outwardly extending flange connected with the central part of the front face of the head and tapering from its rear end to its front end, the front 85 edge of the flange being beveled, the front end merging into the point of the head and forming a point of triangular shape in cross section and a handle detachably connected with the shank whereby tie wires can be cut with 90 the operator located a distance from the wires.

In testimony whereof I affix my signature.
EDWARD WYATT DRENNAN.
